UNITED STATES PATENT OFFICE

ANDREW MAIN, OF CLEVELAND, OHIO, ASSIGNOR, BY MESNE ASSIGNMENTS, TO CLEVE-
LAND FARE BOX AND FOUR-WAY LOCK CO., OF CLEVELAND, OHIO, A CORPORATION
OF OHIO

JAIL LOCK

Application filed June 26, 1930. Serial No. 463,954.

This invention relates to lock mechanisms of the rotary plug and cylinder type, its object being to provide such a mechanism wherein the plug alone, or the plug and cylinder together, may be removed from the front face or wall of the lock mechanism without access to any other face thereof and by an operation relatively difficult to an unauthorized person and inevitably leaving traces of its performance, but capable of being readily performed by an authorized person with ordinary tools or equipment, the plug and cylinder mechanism being also so designed that reinsertion of the parts cannot be performed without the presence of the requisite key.

Further objects of the invention are in part obvious and in part will appear more in detail hereinafter.

In the drawings, Fig. 1 is a sectional elevation upon the line 1—1, Fig. 8; Figs. 2, 3, 4, 5 and 6 are sectional views upon the lines 2—2, 3—3, 4—4, 5—5 and 6—6, Fig. 1, respectively; Fig. 7 is a detail view corresponding to Fig. 1 and illustrating a modification; Fig. 7a is an end view thereof; Fig. 7b is a view of the key; Fig. 8 is a front elevation of the lock; Fig. 9 is a rear elevation of the casing cover; Fig. 10 is a front elevation, the casing cover being omitted to expose interior parts; Fig. 11 is a sectional plan view, somewhat diagrammatic, showing typical cell construction; and Fig. 12 is a front view of a part of the cell.

While the invention is useful and may be embodied in lock mechanisms of any type and for any purpose, nevertheless the invention finds an important application in jail locks, and for convenience, but not in any sense of limitation, is illustrated as applied to such a lock.

In most prior lock mechanisms of the pin tumbler or relatively rotatable plug and cylinder type, removal of the plug and cylinder members from the lock is impossible without access to some other than the front face of the lock casing, where the plug and cylinder are accessible for key insertion. For example, in mortise locks, such as are used in doors, the rotary cylinder and plug are held in place by a screw exposed at the end edge of the door

and the cylinder and plug cannot be unscrewed or removed without access to said set screw, and even then only by unscrewing the cylinder and plug together, or as a unit. Again, in other locks of this general type, the bolt mechanism actuated by the rotary plug is enclosed within a casing, fastened, for example, to the back of the door, and to remove the cylinder and plug mechanism access to said casing is necessary so that it can be opened up to release the plug and cylinder, which are ordinarily attached to the inside of the front wall or face of the lock casing and almost invariably carry some part so large that the cylinder and plug unit cannot be removed through the usual round hole in the casing wall through which they extend.

This condition has given rise to very grave difficulties with prison locks, such as are employed to lock the sliding or other doors of confinement cells. For example, in the Ohio penitentiary at Columbus the bolt mechanism for the cell doors, including its enclosing casing, is completely housed or enclosed within the cell partition or wall, which is formed of metal plates riveted or welded in place as a permanent substantially integral part of the construction of the building or cell block. The only exposed or accessible parts of such locks are the end of the pivoted bolt or latch and the ends of the relatively rotatable cylinder and plug members. As a result of the recent fire at said penitentiary, the prisoners are adopting the most extreme expedients to prevent being locked in their cells at night. Many prisoners have secreted nails or the like which they drive into the key opening so that either the nail cannot be removed or it mutilates the tumbler mechanism and renders it inoperative. As a result, it is impossible to thereafter lock the cell until the tumbler mechanism is repaired or replaced, which requires physical removal of an area of the plate metal of the cell wall by burning it out with an acetylene torch or the like to gain access to the lock casing which encloses or houses the bolt mechanism. After the lock is repaired it must be reinserted and a metal plate welded in to replace the part taken out. The entire job takes a matter of

a day or two and at a cost of almost one hundred dollars.

The present invention is aimed to provide lock mechanism capable of being permanently housed or enclosed in metal plates or other structures, as with former jail locks, and exposing no additional parts for access by unauthorized persons, but in which, when a nail or the like is driven into the key hole, or the tumbler mechanism is mutilated in the manner described, or otherwise, the mutilation is unavoidably detected and it is possible to very easily and conveniently take out the cylinder and plug members and repair or replace them without any necessity of burning out a part of the metal plates of the wall itself, as heretofore, thereby not only reducing the cost and time necessary for the repair or replacement job, but also avoiding the application of intense heat to the neighborhood of the lock mechanism and preventing its detrimental effect upon the delicate tumblers and other parts of the lock mechanism.

The lock shown in the drawings comprises a suitable casing including a box-like body or container 1 provided with a cover wall 2 attached thereto in any suitable manner, such as by screws 3. The casing encloses any ordinary form of lock mechanism, such as the latch or bolt 4 pivoted to swing in a vertical plane on the pin 5 and having a hooked latch end 6 which extends outwardly for engagement with a part of the sliding door (not shown) to be locked, the other arm of the bolt carrying a hammer shaped head 7, one end of which is adapted to be depressed by an arm or lever 8a on an unlocking or releasing member 8 having a post 9 journalled within the casing and provided with suitable means by which it may be actuated by the main rotary plug mechanism, such as a pair of suitable driving recesses 10 shown as of crescent shape and adapted to receive similarly shaped operating projections 11 on the rear end of the rotary plug. The other end of the hammer head of the latch lever cooperates with a projection or shoulder 12 on the dead bolt 13 having a recess 14 adapted to receive a crank pin 15 on the arm 16a of a dead bolt unlocking or releasing member 16 which is operatively connected to the rear end of the rotary plug of the dead bolt operating device by connections 10a, 11a similar to those before described. It will be observed that each of the two rotary plugs is assembled with and disassembled from its unlocking or releasing member 8 or 16 by relative longitudinal motion in the direction of the axis of the plug, and without relative rotation between the plug and the member which it operates, which feature will be referred to hereafter.

In the present lock mechanism, the casing contains two members, to wit, the latch lever and the dead bolt, which are enclosed within the casing by its cover and are adapted to be

separately actuated, each by its own relatively rotatable plug and cylinder members, the latter being carried by the cover of the lock mechanism. The arrangement of the parts is such that the entire casing and cover and all parts contained therein, can be permanently housed within the riveted or welded steel plates of the cell wall conventionally illustrated at 17, Fig. 11, said plates having openings through which extend the projecting ends of the two cylinder and plug mechanisms and through which the latter are removable, as will appear.

For the most part description of one cylinder and plug mechanism will suffice for both. At each of the proper points the cover wall of the casing carries a threaded sleeve portion or member 18. Usually this threaded sleeve is made either as a part of the cover itself or it may be permanently or removably attached to the inside surface of the cover plate. It need not be and usually is not removable through the circular opening 18a in said plate. Into said sleeve is threaded the lock cylinder 19 in which rotates the plug 20. The cylinder and plug are interconnected by suitable tumbler mechanism, which is preferably of the lever type, as illustrated in a prior Patent No. 1,564,883, granted Dec. 8, 1925 to James A. Muzzio. The tumbler levers 21 are mounted in longitudinal slots 22 in the plug, the pivot pins of said tumblers and the springs thereof being held in annular grooves 23 of the plug, as in said patent. Four sets of two tumblers each are distributed circumferentially around the central longitudinal axis, as a result of which the key 24 is of cruciform shape in cross section, although it may also have a square driving portion 24a fitting and entering a like portion 24b of the plug for rotating the latter. The tumbler levers cooperate with longitudinal slots 25 in the inner surface of the wall of the cylinder, and said slots extend continuously from end to end of the cylinder, being formed by a through broaching operation. The outer ends of said slots, as well as a portion of the end of the plug, may be covered by a plate or washer 26, which is a driving fit in a countersunk recess of the cylinder member.

When the cylinder and plug members are in operative position, with the plug projections 11 engaging the recesses 10, the cylinder and plug are held in place by a sleeve or collar 27 attached to the lock wall by screws 28 having their heads deeply countersunk in recesses of the sleeve. Also, rotation of the cylinder in the casing wall is prevented by any suitable means, such as by pins or projections 29 on the cylinder engaging in recesses 30 of the collar 27. Further, said collar may be provided with an inwardly extending flange 31 which covers either the edge of the washer 26 or even its entire area,

although this is not necessary. In the finished construction, the holes in which the heads of the screws 28 are deeply countersunk are filled with small plugs 32 of brass 5 or the like, which are driven in tightly and then finished off smooth to a polished surface.

In this lock, when a prisoner drives a nail into the key opening or otherwise injures it 10 so that it cannot be actuated by usual means, the repair man drills out the small plugs 32, giving him access to the screws 28, which he thereupon removes. This releases the collar 27, which is taken out, thereby releasing the 15 cylinder 19 for rotation.

As before stated, the operating connections 10, 11 between each plug and the member which it actuates are assembled and disassembled by relative longitudinal motion 20 alone, and without relative rotary motion, whereas each cylinder is assembled and disassembled with its sleeve 18 by a screwing operation alone. The two motions, longitudinal and screwing, of the plug and cylinder 25 respectively, cannot be performed unless the tumbler levers of the lock are in release or unlocked position. If it is possible to insert the key into the plug and move the tumblers to release position, that is done, 30 and by holding the key in the plug to maintain the tumblers in release position and to prevent plug rotation, the lock cylinder 19 may be rotated to unscrew it from its sleeve 18, thereby simultaneously removing both 35 the cylinder and the plug from the lock. These two parts may then be replaced by other like parts in proper operative condition, to insert which it is again necessary to have the key in place in the plug so that the 40 tumblers are and may be maintained in release position. With the key in place in the plug, the cylinder may be screwed into the sleeve 18 to its home position, care being taken to see that the operating projections 45 11 register properly with and enter the recesses 10 by longitudinal motion. Upon full insertion of the lock cylinder, the collar 27 is laid in place, its fastening screws 28 are inserted, and new plugs 32 are driven in and 50 filed off.

The operation of removing a cylinder and plug together, or of reinserting a cylinder and plug together, with the key in place in either case, is usually termed a "floating operation", the plug being "floated" longitudinally into and out of driving relation with its member 8 or 16, by the rotation or screwing of the cylinder. As a result, no new lock plugs and cylinders can be inserted into 55 any lock in a prison without the presence of an authorized key, and if a single master key is kept solely in the possession of one trusted authorized official, the prison authorities may avoid any possibility of insertion 60 of a plug and cylinder into a lock unless it

is actually equipped with tumblers and those tumblers are of proper conformation with an authorized key. This prevents any possibility of a prisoner removing a plug and cylinder and restoring them with the tumblers 70 removed, thereby removing the combination features from the lock and making the plug capable of rotation by an ordinary screw driver.

In addition, the lock mechanism is usually 75 so formed that removal of the plug and/or cylinder unavoidably and inevitably leaves traces which are difficult of erasure, so that, for example, if a plug and cylinder are taken out by an unauthorized person, the exposed parts of the lock will inevitably leave 80 evidence of that fact and arouse inquiry. In the lock so far described, the drilling out of the small plugs 32 leaves such traces and other suitable arrangements will be described 85 hereafter.

When it is impossible to insert a key and remove the cylinder and plug together, due to inability to move the tumblers to release 90 position for the "floating" operation, the cylinder and plug may be removed in another way. For example, in the arrangement shown in Fig. 1, the washer 26 can be pried out with a screw-driver or like tool, thereby affording direct access to the end of 95 the plug, which, regardless of the position of the tumblers carried by it, can thereby be drawn out separately and alone by endwise movement, because the tumbler levers will slide freely along the wall of the cylinder or along its grooves when the washer 26 is removed. This is because the entire plug, including its operating projections 11, is of 100 no greater diameter at any point in its length than the diameter of the through hole 105 in the cylinder in which it rotates.

Upon removal of the plug, the cylinder 19 can be readily unscrewed and new parts 110 can be inserted in the same manner before described, but the new parts can only be reinserted by the "floating operation" and in the presence of an authorized key, with advantages as before.

The washer 26, while a driving fit in the recess in which it lies, is usually also connected to the cylinder by one or more small dowel pins 26a, made of steel, whereas the cylinder and washer are of brass. Therefore, when the washer 26 is pried out with a screwdriver or other implement, the steel dowels will not break, but will pull or shear 115 out the small over-lying pieces of brass of the cylinder at 26b, which leaves inevitable traces of the removal of the washer, for purposes before described. The collar 27 may carry an inwardly extending flange 31 covering the edge of the washer, as shown in Fig. 7, in which case the collar 27 must be removed before washer 26 may be pried out, 120 125 130

but in Fig. 1 the washer 26 at all times is exposed over its full area.

Fig. 7 also illustrates the plug 20 provided with an extension 20a at its exposed end extending out to the face of the washer 26, making it possible to provide the end of the plug and the adjacent face of the washer with cooperating relatively movable indicating means, such as the shallow grooves 40, 41, filled with paint or enamel, and which serve to visibly indicate at all times the condition of the lock mechanism, whether locked or unlocked. For example, these two indicating marks can be so placed upon the stationary washer 26 and rotatable plug 20 that the two marks register when the plug is in locked position and are out of registration when in release position, or vice versa. The washer 26 in this case has two opposite edge portions cut away or flattened, as at 26c to furnish entrances for a prying tool for its removal, said entrances being normally covered or concealed by the flange 31.

In all forms, by relatively simple operations requiring no other implements than a drill and screw driver, and without any necessity of burning out a part of the permanent plates of the cell wall, it is possible to repair and replace the cylinder and plug members without access to any other part of the lock casing than what is ordinarily accessible. Moreover, the arrangement is such that unauthorized persons cannot readily remove the lock parts, due to the necessity for use of a drill. As a result, the prisoners cannot take out the cylinder and plug and remove the tumblers and restore the parts in inoperative form. Again, the lock mechanism is of a type in which, if the plug is removed separately from the cylinder, its springs immediately throw or project the tumblers out of their slots in the plug so that the tumbler levers become mixed up and cannot be restored in proper position and order with respect to the key, but a new set of tumblers and a proper key therefor must be inserted by an authorized person.

Other advantages will readily occur to those skilled in the art.

55 What I claim is:

1. Lock mechanism of the character described, comprising a lock casing, bolt operating parts therein, a combination unit including relatively rotatable cylinder and plug members, said cylinder being attached to the casing and removable through its front wall, said plug having operating connections with the bolt operating parts capable of assembly and disassembly by motion in the direction of the plug axis, the plug and its operating connection being endwise removable through the key end of the cylinder in disassembling, and a collar removably attached to the front wall of the casing

and having interlocking relation with the cylinder to prevent rotation thereof.

2. Lock mechanism of the character described, comprising a lock casing, bolt operating parts therein, a combination unit including relatively rotatable cylinder and plug members, said cylinder having threaded connection with the front casing wall and being removable through an opening therein, and the plug having an operating connection with the bolt operating parts capable of assembly and disassembly by motion in the direction of the plug axis.

3. Lock mechanism of the character set forth and claimed in claim 1, including a member attached to the outer end of the cylinder by a frangible connection and arranged to confine the plug therein.

4. Lock mechanism of the character set forth and claimed in claim 1, wherein all parts of the rear end of the plug at all times are located within the outer boundary of the tumbler carrying part of the plug, whereby the plug may be withdrawn endwise through the key end of the cylinder.

5. Lock mechanism of the character described, comprising a lock casing, bolt operating parts therein, a combination unit including relatively rotatable cylinder and plug members, means to attach said cylinder to the casing and said cylinder being removable through the front wall thereof, and said plug having operating connections with the bolt operating parts capable of assembly and disassembly by motion in the direction of the plug axis, the plug having a series of tumbler levers and the cylinder having cooperating grooves therefor extending without obstruction from end to end thereof, whereby the plug may be withdrawn from either end of the cylinder in disassembling.

6. Lock mechanism of the character described comprising a lock casing, bolt operating parts therein, a combination unit including relatively rotatable cylinder and plug members, and means for attaching said cylinder to said casing, said cylinder being removable through the front wall of said casing, said plug having detachable operating connections with the bolt operating parts capable of assembly and disassembly by motion in the direction of the plug axis, the means for attaching said cylinder to said casing including a collar removably attached to the front wall of the casing and having interlocking relation with the cylinder to prevent rotation thereof.

7. Lock mechanism of the character described comprising a lock casing, bolt operating parts therein, a combination unit including relatively rotatable cylinder and plug members, said cylinder being attached to the casing and removable through its front wall, and said plug having operating connections with the bolt operating parts capable

of assembly and disassembly by motion in the direction of the plug axis and said plug being endwise insertible into and removable through the key end of the cylinder in assembling and disassembling, and a collar removably attached to the front wall of the casing and having interlocking relation with the cylinder to prevent rotation thereof.

8. Lock mechanism of the character described comprising a lock casing, bolt operating parts therein, a combination unit including relatively rotatable cylinder and plug members, said cylinder being removable through the front wall of said casing, means for attaching said cylinder to said casing, and said plug having detachable operating connections with the bolt operating parts capable of assembly and disassembly by motion in the direction of the plug axis, and relatively movable cooperating means on the cylinder and plug members for indicating their relative positions.

9. Lock mechanism of the character described comprising a lock casing, bolt operating parts therein, a combination unit including relatively rotatable cylinder and plug members, said cylinder being removable through the front wall of said casing, means for attaching said cylinder to said casing, said plug having detachable operating connections with the bolt operating parts capable of assembly and disassembly by motion in the direction of the plug axis, the means for preventing removal of said cylinder from said casing including a collar removably attached to the front wall of said casing and having interlocking relation with the cylinder to prevent rotation thereof, said collar having countersunk recesses, fastening screws for said collar having their heads within said recesses, and filler plugs for said recesses.

10. Lock mechanism of the character set forth and claimed in claim 7 including a member attached to the outer end of the cylinder by frangible connection arranged to confine the plug therein.

11. Lock mechanism of the character set forth and claimed in claim 7 wherein all parts of the rear end of the plug at all times are located within the outer boundary of the tumbler carrying parts of the plug, whereby the plug may be withdrawn endwise through the key end of the cylinder in disassembly.

55 In testimony whereof I hereby affix my signature

ANDREW MAIN.
